(57) **CLAIM**

The ornamental design for a carrying container with water bottle, as shown and described.

DESCRIPTION

FIG. 1 is a perspective view of a carrying container with water bottle showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines immediately adjacent the shaded areas represent the bounds of the claimed design while all other broken lines depict portions of the carrying container with water bottle only; the broken lines form no part of the claimed design.
